UNITED STATES PATENT OFFICE

ISAIAH B. KIMMEL, OF JOHNSTOWN, PENNSYLVANIA

TONGUE SWITCH

Application filed September 24, 1931. Serial No. 564,938.

This invention relates to railway switches and more particularly to railway switches of the movable tongue type.

One of the objects of the invention is to provide an improved movable tongue switch structure.

Another object of the invention is to provide means to prevent the tongue joint from being displaced from its desired position by traffic loads passing therethrough.

Another object of this invention is to improve switch tongue pivoting means in a railroad switch of the movable tongue type.

Other objects and advantages will become apparent as the present invention is more fully disclosed.

In accordance with the objects of the present invention I have found that a marked increase in the life and durability of a movable tongue switch may be obtained by providing a double bearing pivoting means for the tongue heel and by providing means to take traffic loads off from the said pivotal joint. I also prolong the operating life of such a switch by providing means to prevent vertical displacement of the switch tongue during the passage of traffic loads therethrough. The specific pivoting means of the present invention comprises a double bearing structure wherein a hollow pin member integral with the tongue heel is provided having inside and outside bearing faces, the outer bearing face engaging in a bearing recess in the switch base and the internal bearing face being engaged by a tubular extension element upon a plate member adapted to be positioned upon and over the tongue heel and to be rigidly attached to the switch base, the plate member having rail extensions forming flange ways upon its upper face adapted to align with the rails of the switch base to carry the car wheels over the pivotal joint. The full weight of the railroad cars passing through the switch is thus taken off from the tongue heel pivotal joint and deleterious displacement of the tongue point due to rocking of the heel bearing or pivotal joint is thereby eliminated. The area of the plate element may be extended to cover lateral base extension mem-

bers on the tongue, if desired, as will be more fully hereinafter disclosed.

Before further disclosing the nature and scope of the present invention reference should be made to the accompanying drawings wherein—

Figs. 1 to 7 inclusive illustrate one modification of the present invention, and

Figs. 8 to 12 inclusive illustrate a second modification of the same.

Referring to Figs. 1 to 7 inclusive, Fig. 1 shows a top view of a simple type of movable tongue switch incorporating the novel type of heel bearing and protecting plate of the present invention;

Fig. 2 is a sectional view along plane 2—2, Fig. 1;

Fig. 3 is a top view of the tongue switch showing the hollow heel extension member;

Fig. 4 is a top view of the protecting plate showing the rail extension or flangeway means thereon;

Fig. 5 is a sectional view of the main switch casting showing the bearing recess therein;

Fig. 6 is a cross-sectional view along plane 6—6, Fig. 1;

Fig. 7 is a cross-sectional view along plane 7—7, Fig. 1;

Fig. 8 is a top view of the second type of switch;

Fig. 9 is a sectional view along plane 9—9, Fig. 8;

Fig. 10 is a cross-sectional view along plane 10—10, Fig. 8;

Fig. 11 is a cross-sectional view along plane 11—11, Fig. 8; and

Fig. 12 is a top view of the switch tongue with the heel located in position in a switch base recess and the protecting plate 4 in position to form the double bearing pivotal joint, the flange extensions of said plate being broken away to illustrate the overlapping feature involved.

In Figs. 1 to 7 inclusive, 1 is a usual type of switch base; 2 a movable switch tongue; 3 a hollow pin extension member on the tongue heel; 4 a protecting plate adapted to be seated in seat 16 of base 1 and to be rigidly attached by means 5 to the said switch base 1 and 6 is a bearing recess in the switch base into which

the hollow pin extension 3 on switch tongue 2 is to be inserted. The upper face of plate 4 carries rail extension members adapted to be aligned with the rails of the switch base to form flangeway recesses 7 and 8 and the under face of plate 4 carries a tubular extension element 9 having an outside diameter substantially the same but smaller than the inner diameter of hollow pin member 3 and adapted to be positioned therein. The diameter of bearing recess 6 is substantially the same as but larger than the outside diameter of hollow pin member 3. The abutting faces of elements 3, 6 and 9 are adapted to serve as bearing faces. Space 10 in the tubular extension element 9 may be packed with oil waste to facilitate the bearing action of the elements. When plate 4 is rigidly attached to base 1 by means 5 hollow pin member 3 should be free to rotate in recess 6 within the limited degree required for the desired switching action.

Referring to Figs. 8 to 12 inclusive, an adaptation of the double bearing pivotal switch joint and protecting plate feature of Figs. 1 to 7 inclusive to a different type of movable tongue switch is shown.

The movable tongue switch of Figs. 8 to 12 inclusive comprises a switch base 1, a movable switch tongue 2 having a hollow pin extension member 3 upon the tongue heel thereof, as in Figs. 1 to 7 inclusive. The tongue element 2, however, has laterally extending flange members 11 on the base thereof serving the dual purpose of supporting the switch tongue upon the switch base 1 and of providing means such as indicated at 12 to engage with a spring switching means 13. I propose to extend sections 14 and 15 of protective plate 4 to entirely cover and protect the flange extension members 11, in a manner clearly indicated in Figs. 8 to 12 inclusive. The entire plate can be attached to the switch base 1 by means 5 as indicated. This provides a complete protecting shield for the movable switch tongue and positively prevents vertical displacement of the tongue from its desired switching position while traffic loads are passing through the switch.

From the above description and drawings it is apparent that there may be many modifications and departures made in the present invention without departing essentially from the nature and scope thereof as may be set forth in the following claims:

What I claim is:

1. A railroad switch of the movable tongue type comprising a switch base, a movable switch tongue and double bearing pivotal means for said switch tongue, said means comprising a hollow pin extension member on the switch tongue heel, bearing faces in the inner and outer surfaces of said pin extension member, a bearing recess in said switch base adapted to receive the pin

extension member and to engage the outer bearing surface thereof, and a protecting plate member adapted to be seated upon the switch base above the tongue heel and to be firmly secured thereto, a tubular extension member upon the under surface of said plate adapted to enter the hollow pin member of said tongue heel and to engage the bearing surface thereof, and rail extension means upon the upper face of said plate adapted to align with the switch base rails to form continuations thereof over and across the switch pivoting joint. 70

2. A railroad switch of the movable tongue type comprising a switch base, a movable switch tongue having laterally extending base flanges, double bearing pivotal means for said switch tongue, and means to prevent vertical displacement of the switch tongue during the passage of a traffic load therethrough, said double bearing switching means comprising a hollow pin extension member on the switch tongue heel, bearing faces in the inner and outer surfaces of said pin extension member, a bearing recess in said switch base adapted to receive the pin extension member and to engage the outer bearing surface thereof, and a protecting plate member adapted to be seated upon the switch base above the tongue heel and to be firmly secured thereto, a tubular extension member upon the under surface of said plate adapted to enter the hollow pin member of said tongue heel and to engage the bearing surface thereof and said means to prevent vertical displacement of the switch tongue comprising rail extension means upon the upper surface of said plate adapted to align with the switch base rails to form continuations thereof over and across the switch pivotal joint, and extension means on said plate adapted to extend in overlapping relationship with the laterally extending base flanges on said switch tongue. 85

In witness whereof, I have hereunto signed my name. 90
